CLAIM

The ornamental design for a cue stick mat, as shown and described.

DESCRIPTION

FIG. 1 is a perspective top front left view of a cue stick mat showing my new design;

FIG. 2 is a perspective top rear right view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.
